Patented Mar. 28, 1916.

UNITED STATES PATENT OFFICE.

OSCAR L. LAWSON AND JAMES H. REED, OF LYNN, MASSACHUSETTS.

NEEDLE-GUIDE.

1,177,118.

Specification of Letters Patent. Patented Mar. 28, 1916.

Application filed March 23, 1915. Serial No. 16,452.

To all whom it may concern:

Be it known that we, OSCAR L. LAWSON, a subject of the King of Sweden, and JAMES H. REED, a citizen of the United States, residing at Lynn, county of Essex, State of Massachusetts, have invented a certain new and useful Improvement in Needle-Guides, of which the following is a specification, reference being had therein to the accompanying drawings.

Our invention relates particularly to shoe sewing machines of the general type shown in the prior application of Oscar L. Lawson filed May 29, 1914, Ser. No. 841,752; and has for its object to provide a needle guide which will support the curved hooked needle at the time when it is being pushed into the hole formed in the work by the awl.

It is important that the needle guide shall support the needle at a point as closely adjacent the surface of the work as possible; that it shall be out of the way when the needle rises with the loop; and that it will nevertheless have its lowermost position varied in accordance with the thickness of the work. Also, it is desirable to have it support the needle when the needle is out of the work and is then subjected to the strain placed upon it by the under thread. It will be understood that the tension of the under thread and the action of the loop spreader both tend to subject the needle to considerable strain. We accomplish these results by controlling the lowest position of the needle guide by the presser foot. We believe ourselves to be the first to control the position of a needle guide by the presser foot and therefore desire to claim this invention broadly.

The invention will be fully understood by reference to the following specification taken in connection with the accompanying drawings, and the novel features thereof are pointed out and clearly defined in the claims at the close of this specification.

In the drawings, Figure 1 is a side elevation of a shoe sewing machine embodying our invention, the parts being in the position occupied when the needle and needle guide are at the top of their stroke. Fig. 2 is a similar view showing the position of the needle guide when the needle is in the work. Fig. 3 is a top plan view of the parts shown in Fig. 1. Fig. 4 is a side elevation of the elbow lever on which the needle guide is mounted. Fig. 5 is a front

elevation of the needle guide and Fig. 6 is a side elevation of the needle guide.

Referring to the drawings, and particularly to Fig. 1, there is shown at 10 the presser foot, at 11 the needle, at 12 the awl, at 13 the work support, and at 14 the shuttle, these parts being in general the same as those described in said prior application to which we have heretofore made reference.

The needle 11 is supported on a needle segment 15 which oscillates about the shaft 16. On a sleeve 17 (see Fig. 4) having two arms 18 and 19 is placed the needle guide 20, (see particularly Figs. 5 and 6). The needle guide proper consists of a block 20 having a screw threaded stud 21 integral therewith, said screw threaded stud 21 is adapted to pass through the hole 22 in the arm 19 and to be secured in position by a nut 23, see Fig. 3. The block 21 has formed therein a curved hole 24, see Fig. 6, of a size and shape corresponding to the size and shape of the needle. For convenience the sleeve 17 together with the two integral arms 18 and 19 may be referred to as the needle guide support. The needle guide support is oscillated on the shaft 16 in time with the stitch forming instrumentalities by means of a cam 24, mounted on the cam shaft 25.

At 26 is shown a cam lever pivoted at 27 to a frame of the machine and provided with a cam follower 28 engaging the cam groove 29 in the cam 24. The cam lever 26 is connected with the arm 18 of the needle guide support by two links 30 and 31 which together form a toggle joint. It will therefore be seen that if the two links 30 and 31 be maintained in a fixed relation one to the other the needle guide support will be oscillated about the shaft 16, and will have a predetermined length of stroke. It will also be seen that the lowermost limit of movement of the needle guide may be varied, if at the proper time in the stroke of the cam lever 26, the two links 30 and 31 are moved relatively to each other *i. e.*, to break the toggle joint, and permit the further upward movement of the cam lever 26 without thereafter changing the position of the needle guide support. For this purpose we provide a member 32 pivoted at 33 to the frame of the machine and having therein a slot 34. Said member 32 which we term for convenience the controller, is also provided with a slot 35 in which is located

a pin 36 fast on the tail of the presser foot supporting member 37. When the presser foot 10 is raised, as for instance when a thicker piece of work is inserted, the tail 5 of the presser foot supporting member 37 is depressed since the presser foot supporting member 37 is pivoted to the frame as shown at 41. The pin 36 is also depressed and the controller 32 is swung about the 10 pivot 33 changing the position of the slot 34. The slot 34 consists of a straight portion *a* and an arc-shaped portion *b* connected therewith. The pin 38 by means of which the proximate ends of the links 30 15 and 31 are connected is movable in the slot and as long as it remains in the straight portion of the slot the links 30 and 31 are maintained in a fixed position relatively to each other. When the pivot pin 38 reaches 20 the arc shaped portion of the slot *b*, the two links 30 and 31 are free to move relatively to each other thereby breaking the toggle and permitting the cam lever 26 to be thereafter moved upwardly without affecting the position of the needle guide. It 25 will therefore be seen that as the cam rotates the needle guide is moved from the position shown in Fig. 1 to the position shown in Fig. 2, and that when the pin 38 reaches 30 the beginning of the slot *b*, the needle guide rests and the remainder of the movement of the cam lever 26 and link 31 produced by the cam 24 is lost motion. It will also be seen 35 that the position of the presser foot changes the height of the point of union between the straight slot *a* and the arc shaped slot *b* so that when the needle guide comes to rest the point is controlled positively by the position of the presser foot. It will therefore 40 be seen that the needle guide always rests at a point practically in contact with the upper surface of the presser foot regardless of the thickness of the work. The movement of the parts is so timed that the needle 45 guide will remain stationary until the needle is about to come out of the work, then

the needle and needle guide move up together until they reach the upper limit of movement. This arrangement is such that the needle is continuously supported and 50 therefore is not likely to be bent and then broken by the strains to which it is constantly subjected.

What we claim is:

1. In a shoe sewing machine, in combination with a presser foot, a needle guide separate from the presser foot and mounted to oscillate toward and away from the work, means for oscillating the needle guide and means under the control of the presser foot 60 to vary the position of the lower end of the path of movement of the needle guide.
2. In a shoe sewing machine, and in combination with a presser foot, a needle guide, means to oscillate the said needle guide, 65 said means including a toggle joint, and a controller the movement of which is controlled by the presser foot operating upon said toggle joint to break the said toggle joint at a point determined by the position 70 of the presser foot.
3. In a shoe sewing machine, and in combination with a presser foot, a needle guide, means to oscillate the said needle guide, 75 said means including a toggle joint, a controller having a slot, one portion of which is straight and another portion of which extends at an angle to said straight portion, a pivot for said toggle joint guided in said slot, said controller being connected to the 80 presser foot whereby the position of the apex of the slot is varied by the presser foot to break the toggle joint at a point determined by the position of the presser foot.

In testimony whereof we affix our signatures, in presence of two witnesses.

OSCAR L. LAWSON.
JAMES H. REED.
